US0D1026172S

(12) **United States Design Patent** (10) Patent No.: **US D1,026,172 S**
(45) Date of Patent: ** May 7, 2024

(54) **FAUCET SPOUT**

(71) Applicant: **DELTA FAUCET COMPANY**,
Indianapolis, IN (US)

(72) Inventor: **Josh Homesombath**, Milwaukee, WI
(US)

(73) Assignee: **DELTA FAUCET COMPANY**,
Indianapolis, IN (US)

(**) Term: **15 Years**

(21) Appl. No.: **29/774,860**

(22) Filed: **Mar. 19, 2021**

(51) LOC (14) Cl. **23-01**

(52) U.S. Cl.

USPC **D23/255**
